UNITED STATES PATENT OFFICE.

PERRY SNYDER, OF VEILLETTÉ, ALBERTA, CANADA, ASSIGNOR OF ONE-HALF TO
JOHN ALEXANDER MITCHELL, OF PAKAN, ALBERTA, CANADA.

RAKE.

1,372,464.

Specification of Letters Patent. Patented Mar. 22, 1921.

Application filed March 17, 1919. Serial No. 283,216.

To all whom it may concern:

Be it known that I, PERRY SNYDER, a subject of the King of England, residing at Veillette, in the Province of Alberta and 5 Dominion of Canada, have invented new and useful Improvements in Rakes, of which the following is a specification.

This invention comprehends generally improvements in that class of inventions known 10 as harvesters and more particularly relates to a rake.

It is the principal aim and object of the present invention to provide a device of the above mentioned character wherein the bed 15 or rack is adjustably mounted in the frame so that the teeth mounted on the bed may be adjusted into and out of a raking position.

It is an equally important object of the present invention to provide a device of the 20 above mentioned character wherein a follower is slidably mounted on the bed and is designed to be adjusted at times for removing the hay from the rack for stacking purposes while acting in conjunction with the 25 follower is a stacking slide for facilitating the stacking of the hay as it is being removed from the bed.

More particularly the present invention 30 includes provision of a device of the above mentioned character wherein a coöperative hitch is employed in conjunction with the frame and with the follower for assuring of the propelling of the frame and for operating the follower at the desired time independently of the frame.

It is a more specific object of the invention to provide a device of the above mentioned character wherein improved means is employed for adjustably supporting the 40 forward end of the bed in the frame; and also to provide improved means for mounting the raking teeth.

Other improvements and novel details in the construction and arrangement of the 45 various parts of the apparatus will be brought out more in detail in the description to follow, which for a clear understanding of the invention should be considered in connection with the accompanying drawings 50 forming a part hereof, and wherein is disclosed for the purpose of illustration a convenient and satisfactory embodiment of the invention. It is to be noted in this connection that minor changes in the construction 55 and arrangement of parts may be made

without departing from the principle of operation of the various parts.

The invention is clearly illustrated in the accompanying drawings, in which:

Figure 1 is a side elevation of the invention. 60

Fig. 2 is a top plan view thereof.

Fig. 3 is a longitudinal sectional view of the device.

Fig. 4 is a perspective detail of the 65 lower.

Fig. 5 is side elevational view of the stacking slide.

Fig. 6 is a side view partly in section 70 showing one of the teeth.

Fig. 7, is a detail perspective view showing the forward end of one of the subframes.

Similar characters of reference are employed in all of the above described views, 75 to indicate corresponding parts.

Referring now, more particularly, to the accompanying drawings there is provided a main frame comprising spaced side bars 1 connected at their rear ends by a rear cross 80 bar 2. A rear axle 3 is connected to the bar 2 while upon the respective ends thereof are journaled supporting wheels 4. A front U-axle 5 is now employed and has its respective ends 6 journaled through the forward ends of the side bars 1 while the intermediate portion of the axle supports the forward cross piece 7.

A bed or rack generally designated by the numeral 8 is pivoted as at 8' to the cross bar 90 2 and consists of a base 9 and spaced side pieces 10 connected by a rear end piece 11 and having their upper edges inclined as at 12. A flange 13 depends from the forward edge of the base 9 while also secured to and 95 depending from the undersurface of the base 9 rearwardly of the flange 13 is another transversely disposed flange 14. The flanges 13 and 14 are provided with a plurality of alining openings 15. Elongated rake teeth 100 16 are now employed and are slidably disposed through the opposed slots 15 in such a manner that the front portions extend longitudinally from the base 9 being yieldingly held forwardly by coiled expansion springs 105 17 disposed about the inner portions of the teeth 16 and have their respective ends bearing against the flange 14 and transverse cotter pins 18 arranged through the inner portions of the teeth 16 rearwardly of the flange 110 11.

13. Other cotter pins 19 are passed through the inner terminals of the teeth at the extreme inner end and are positioned rearwardly of the flange 14 serving as a means 5 for preventing accidental forward displacement of the teeth from the flanges. It is to be observed particularly, that should the teeth strike a hard object they would be pressed inwardly.
10. As intimated, improved means have been employed for adjustably supporting the forward end of the rake bed within the frame and in reducing this feature of the invention to practice upright posts 20 project 15 from the forward end of the body near the sides thereof. Segmental racks 21 are connected to the side bars 1 near the forward end while hand levers 22 are in turn pivoted by suitable fasteners 23 centrally 20 of the segmental racks and have their angularly bent portions 24 pivoted to the upper ends of the post 20 by means of fasteners 25. In effect these are substantially bell crank levers and it is apparent that by 25 swinging the same about their pivots the forward end of the bed will be raised into an inactive position or lowered into an active position and when in the latter position is preferably supported by the cross bars 30 7. Bell cranked hand levers 26 are pivoted to the upper ends of the hand levers 22 while pawls 27 are slidably connected to the hand levers 22 and operably connected to the bell cranked levers 26 by means of rods 28 35 about which are disposed coiled springs 29 for normally holding the pawls in engagement with any of the teeth of the segmental racks 21 for assuring of the retention of the bed in a predetermined set position.
40. With a view toward providing improved means for propelling the frame and for removing the hay from the bed when a sufficient quantity has been placed thereon a follower plate 30 is employed and is normally disposed near the rear end piece 11 of the bed. Loops 31 are connected to the ends of the follower and are disposed at right angles thereto. Cables 32 have their inner ends connected to the loops 31 while 45 connected near the terminals, which carry whiffle trees 33, are rings 34 designed for engagement with spiral hooks 35 mounted on the forward ends of triangular sub-frames 36 in turn rigidly connected to the upright portions of the axle 5 as at 37. By this arrangement it is apparent that when draft animals are connected to the whiffle trees, which form in effect a side hitch, when the rings are engaged in the 50 hooks 35 the frame will be propelled and when the bed is loaded with hay and it is desired to remove the same therefrom the rings may be disengaged from the hooks so that the follower will be drawn down the 55 bed so as to remove the hay therefrom.

Now when the follower is being moved independently of the frame suitable locking means is employed for holding the frame stationary, in the present instance consisting of suitable flexible elements such as a chain 38 which carries a hook 39 at the outer end designed for engagement with one of the spokes of one of the rear wheels 4. When the hay is being moved from the bed a stacking slide generally indicated by 70 the numeral 40 is employed and consists of spaced runners 41 connected by cross bars 42 while connected to the runners are upright posts 43 which are reinforced by transverse braces 44 to provide a substantial 75 frame for co-operating with the runners for supporting an inclined platform 45 which rises from the forward end of the runners as intimated. The preferred use of the device for raising and stacking is as follows: 80 The levers 22 are first adjusted so that the teeth are arranged in a raking position and when the bed has become filled with hay the locking hooks are attached to the rear wheels while the rings are disengaged 85 from the hooks 35 thus anchoring the frame and causing the follower to be drawn forwardly of the bed by the draft animals and the hay is in this manner removed from the bed and drawn against the high end of 90 the stacker which is anchored a suitable 95 distance forwardly of the frame. Two or three loads are dumped in this manner until a substantial compact body or base for a stack (not shown) is provided, the rings in 100 the meantime, of course, being connected with the hooks 35 subsequent to the placing of the follower in its normal position. Now when the bed has been provided the frame is anchored forwardly of the low end 105 of the stacking slide and by repeating the operation above recited the hay is drawn from the body and up the incline so as to be deposited upon the body of the stack and three or four loads are dumped on the 110 body or base of the stack until the stack is of sufficient height.

What is claimed is:

1. A device of the character described comprising a wheeled frame, a bed having 115 one end swingably connected to the rear end of the frame, spaced flanges depending from the forward end of the bed and provided with opposed openings, elongated rake teeth slidably disposed through the opposed openings, means for preventing accidental displacement of the teeth, coiled springs disposed about the inner portions of the teeth and tensioned to yieldingly hold the teeth forwardly, posts rising from 120 the forward end of the bed, segmental racks carried by the frame, levers swingably connected to the racks and operably connected to the posts whereby when swung the bed will be raised or lowered, and manually op- 130

erable means on the levers for releasably holding the bed in various positions of adjustment.

2. A device of the character described comprising a wheeled frame, a bed having spaced flanges depending from the forward end and provided with opposed openings, elongated rake teeth slidably disposed

through the opposed openings, means for preventing accidental displacement of the teeth, and coiled springs disposed about the inner portions of the teeth and tensioned to yieldingly hold the teeth forwardly.

In testimony wehereof I affix my signature.

PERRY SNYDER.
